(57) **CLAIM**

The ornamental design for a popcorn machine, as shown and described.

DESCRIPTION

FIG. 1 is a front, right, and top perspective view of a popcorn machine, showing my design.

FIG. 2 is a rear, left, and bottom perspective view of the popcorn machine in FIG. 1.

FIG. 3 is a front view of the popcorn machine in FIG. 1.

FIG. 4 is a rear view of the popcorn machine in FIG. 1.

FIG. 5 is a left side view of the popcorn machine in FIG. 1.

FIG. 6 is a right side view of the popcorn machine in FIG. 1.

FIG. 7 is a top view of the popcorn machine in FIG. 1; and, FIG. 8 is a bottom view of the popcorn machine in FIG. 1. The broken lines shown in the drawings are included for the purpose of illustrating portions of the popcorn machine that form no part of the claimed design.
